UNITED STATES PATENT OFFICE.

CLARENCE S. WARREN, OF MILFORD, OHIO.

INDIVIDUAL TELEPHONE-MOUTHPIECE.

1,072,537.

Specification of Letters Patent. Patented Sept. 9, 1913.

Application filed April 13, 1912. Serial No. 690,511.

To all whom it may concern:

Be it known that I, CLARENCE S. WARREN, a citizen of the United States, residing at Milford, in the county of Clermont and State of Ohio, have invented new and useful Improvements in Individual Telephone-Mouthpieces, of which the following is a specification.

This invention relates to improvements in individual telephone mouth pieces, the object of the invention being to provide a mouth piece of this character which may be readily attached to and moved from the mouth piece of a telephone transmitter and by means of which the user of the individual mouth piece may protect himself from danger of contracting some disease from using a telephone to which the public has access, the invention consisting in the construction, combination and arrangement of devices, hereinafter described and claimed:

In the accompanying drawing:—Figure 1 is a side elevation of an individual telephone mouth piece constructed in accordance with my invention, showing the same in use on a telephone transmitter, the latter being indicated in dotted outline. Fig. 2 is a front elevation of the same. Fig. 3 is a detail cross sectional view on the plane indicated by the line *a*—*a* of Fig. 2. Fig. 4 is a rear elevation of a modified form of my individual telephone mouth piece.

In accordance with my invention, I provide a connector 1 which is here shown as a band or ring of sheet metal, open at one side and provided at its ends with outturned portions 2. This connector is arranged to be placed around the enlarged portion *a* of a telephone transmitter and to be clamped thereon by means of a bolt 3 which passes through openings in the outturned end portions 2. This connector is constructed with a series of spaced openings 4.

In connection with the connector, I provide a number of individual telephone mouth pieces 5 each of which is provided at one side with a curved radially arranged arm 6 and at the opposite side with a spring catch 7. The outer end of the curved arm 6 of each individual telephone mouth piece is pivotally connected to the connector and is provided with a cylindrical portion 8 which passes through one of the openings 4 and in connection with that portion of the

connector which forms one side of the said opening, forms a pivotal connection between the individual mouth piece and the connector. When all of the mouth pieces 5 are out of register with the mouth piece *b* of the telephone transmitter, the individual mouth pieces 5 are arranged radially around and spaced from the neck of the transmitter. Any one of the individual mouth pieces may be swung over and applied to the telephone mouth piece and connected thereto detachably by the engagement of the spring catch 7 with one side of the telephone mouth piece, the said catch and the arm 6 coacting to hold the individual mouth piece on the telephone mouth piece while being used.

The mouth pieces 5 will be used by different individuals and each may have a designating number, letter or other symbol. By thus providing a plurality of interchangeable individual mouth pieces for a telephone transmitter, each mouth piece may be used, when desired, only by one individual and all danger of contracting a contagious disease from the use of the telephone will be avoided. By thus providing the connector for attachment to a transmitter, and providing the series of individual mouth pieces with the arms pivotally connected to the connector, all the individual mouth pieces are held conveniently at the telephone and there is no danger of their becoming lost or misplaced and they are accessible to the responsive users and any one of them may be instantly attached to and disconnected from the telephone mouth piece.

In Fig. 4 of the drawing, I show a modified form of my invention, in which the individual mouth piece 9 is adapted to be carried in a pocket and to be connected to and detached from a telephone mouth piece, at will. This individual mouth piece, which is of suitable form, comprises a body having an annular flange or cup 10 and on the rear side of the individual mouth piece at the upper side thereof are a pair of segmental overhanging attaching lips or flanges 11 which may be sprung around and readily removed from the mouth piece of the telephone, as will be readily understood. This individual mouth piece may be made of any suitable material and its attaching overhanging lips or flanges are preferably made

of elastic material which admit of the ready attachment and removal of the individual mouth piece.

I claim:

- 5 1. A connector comprising a band adapted to be placed around a telephone transmitter, and a series of individual telephone mouth pieces each having an arm pivotally connected to the connector, so that each
- 10 individual mouth piece may be applied to and removed from the telephone mouth piece.
- 15 2. A connector comprising a band adapted to be arranged around a transmitting telephone, and a series of individual mouth pieces each having an arm on one side, the

said arm being arranged radially of and pivotally connected to the connector.

3. A connector for attachment to a telephone transmitter and an individual mouth piece pivotally connected to and carried by the connector and adapted to be applied to and removed from the telephone mouth piece, the said individual mouth piece being provided with means to detachably secure it to the telephone mouth piece.

In testimony whereof I affix my signature in presence of two witnesses.

CLARENCE S. WARREN.
